UNITED STATES PATENT OFFICE.

WILLIAM H. CHURCHMAN, OF JANESEVILLE, WISCONSIN.

FURNACE FOR HEATING BUILDINGS.

Specification of Letters Patent No. 29,571, dated August 14, 1860.

To all whom it may concern:

Be it known that I, WILLIAM H. CHURCHMAN, of Janesville, in the county of Rock and State of Wisconsin, have invented a 5 new and useful improvement in the method of warming and ventilating apartments in dwelling-houses and other buildings by air-heating furnaces; and I do hereby declare that the following is a full, clear, and exact 10 description of the same, reference being had to the accompanying drawings, making part of this specification, in which—

Figure 1, is a horizontal section of the improved furnace, at the line A, of Fig. 5. 15 Fig. 2, is a horizontal section of the same, at the line B, of Fig. 5. Fig. 3, is a horizontal section of the same, at the line C, of Fig. 5. Fig. 4, is a front elevation of the said furnace. Fig. 5, is a side elevation of 20 the same. Fig. 6, is a vertical section of the same, at the line D, of Fig. 5, showing also, in section, a pair of ventiducts proceeding from the furnace to one of the apartments of the building to be warmed and ventilated. 25

Similar letters in the drawings, refer to corresponding parts throughout.

The aim of this invention is to supply to dwellings and other buildings a mild, genial, 30 and healthful warmth, similar to that derived from steam and hot-water fixtures, but without their complication and expensiveness, and at the same time to secure a perfect control, of the ventilating currents, 35 whereby the influx of fresh air, either warmed or unwarmed, and the discharge of vitiated air, may be readily graduated to meet any requirement.

The device employed for the accomplishment 40 of these ends consists of an air-heating furnace of peculiar construction, located in the cellar or basement of the building, together with one or more pairs of ventiducts or flues, D—E, E—G, leading from and to 45 each apartment to be warmed and ventilated; whereby the air to be warmed and conveyed to said apartment, may be drawn either directly from the same or from without the building, at the election of the occupant, and the vitiated air rapidly withdrawn and discharged into the open air. 50 By this arrangement which will be more fully described hereafter, it will be seen that the apparatus is made to perform the 55 double office of heater and ventilator.

The furnace walls which may be con-

structed of brick or any other suitable material, are made double, with air-spaces intervening, after the ordinary manner of hot-air furnaces.

The air-heating surface is made up of a number of compound drums, or tubular rarefiers, C—c—C', through which the ventilating currents are made to pass in their way from and to the several apartments of the building, a moderate degree of heat being applied to the exterior surfaces of these rarefiers and communicated, through their substance, to the air within. These rarefiers may be constructed of iron, 70 either wrought or cast, or of any other suitable metal, and even of terra cotta or any like substance. They differ in size and number according to the building in which the apparatus is employed, and are disposed in 75 one or more regular series within the walls of the furnace, as indicated by the drawing.

The appliances for generating the heat and diffusing it uniformly over the extended surfaces of said rarefiers, whereby a mild, 80 healthful temperature is imparted to the ventilating currents, consist of the fire-space with its grate, S; the central smoke flue, d, which leads to the back of the furnace and directly into the chimney, e, when the 85 damper, T, is open; the side flues, b, b, through which, when the damper, T, is closed, the smoke and gases return to the front of the furnace; the cast iron plates, V, V, V, which, cover the fire-space and smoke 90 flues just described, transmitting the heat from these to the chamber above, among the rarefiers; and the openings, X, X, in said plates, V, V, through which the smoke and gases, upon their return to the front, 95 ascend into the heating chamber, or main body of the furnace passing among the rarefiers on their way back to the chimney, e, and imparting most of their heat to the same before reaching the exit opening, a;—which 100 opening, a, is placed at the bottom of the chamber, rather than the top, in order to retain as much of the heat as possible.

U, is a rod for operating the damper, T; Y, Y, are iron covers to the return flues, b, b, 105 which can be removed for cleaning out the same; and, Z, is a door for entering the furnace to make repairs etc.

When a strong, direct draft is required, as during the starting of the fire the damper, 110 T, is opened; but at all other times said damper is kept shut, so as to return the

smoke and gases to the front of the furnace, and pass them among the rarefiers, as described, thus effecting a very important saving in the expenditure of heat.

5 With the arrangements here described, the furnace is designed for burning anthracite coal, coke or dry wood. When bituminous coal or green wood is the fuel used, the smoke is not allowed to escape into the 10 heating chamber, but returned from the front of the furnace to the chimney through a T pipe, connecting the openings, X, X, with the exit opening, a.

In the side walls of the furnace are longitudinal hot-air chambers, A, A, with which the rarefiers communicate through their upper drums, C, said chambers being united by a channel or flue, A', constructed in the front wall. In these hot-air chambers, A, A, 20 and their connecting flue, A', are placed transversely, several stop-dampers, M, M, M, O, of original construction, for dividing the same, at pleasure, into subchambers of greater or less size according to the amount 25 of warmth or ventilation required at any given time for each of the several apartments of the building. Correspondent to said hot-air chambers, and below them in the side walls, are cold air-chambers, B, B, 30 with which the rarefiers also communicate, through their lower drums, C', said cold-air chambers being likewise united by a flue, B', and provided with similar stop-dampers, N, N, O', for dividing them as in the case of 35 the hot-air chambers.

In the described hot-air chambers, and covering their entire bottoms which are composed of thin iron, are shallow evaporating pans, P, P, to be kept supplied with water 40 for moistening the rarefied air as it leaves the furnace. Immediately under these pans, and separated from them only by the thin iron plates upon which they rest are horizontal chambers or flues, R, R, extending 45 through their entire length, and communicating by suitable openings with the interior of the furnace; which openings are provided with registers or dampers, Q, Q, for controlling the amount of heat admitted to the 50 evaporators.

Having thus given a detailed description of the furnace proper, I now proceed to describe the remaining portions of the apparatus, which are employed in the application 55 of my improved system to the purposes of warming and ventilation, as follows;—from the described hot-air chambers, A, A, to each of the apartments to be warmed and ventilated, proceed one or more ventiducts or 60 flues, D—F, for the ascent of the heated air, the number of the same depending upon the size of the apartment, these ventiducts instead of terminating in the apartments, as is the case with ordinary hot-air flues, are 65 continued in an upward direction through

or past the same in the walls to appropriate outlets in the top of the building, and each provided with two registered openings, into the apartment for which it is designed, one, K, near the floor and the other, J, near the 70 ceiling of the same; while just above each of said openings is inserted a damper, L, for cutting off the ascending current of warm air, at pleasure, and throwing it into the room. Correspondent to said hot-air flues, 75 just described and proceeding from the cold-air chambers, B, B, is a like number of ventiducts, E—G, for the descent of the cold air to the furnace. These last named ventiducts which are located on opposite sides 80 of the rooms from their corresponding hot-air ducts when practicable, are likewise continued through or past the respective apartments for which they are designed, to appropriate outlets above, and provided with 85 similar registered openings, H, I, and dampers, L, for controlling the point from which the cold air shall be drawn, as well as the supply of the same. Now by suitable adjustments of the registers at, H, I, J, K, 90 and their accompanying dampers, L, together with the stop-dampers, M, O, in the hot-air chambers, A, A, and connecting flue, A', and the corresponding stop-dampers, N, O', in the cold-air chambers, B, B, and 95 connecting flue, B', the ventilating currents may be perfectly controlled, whatever be the force or direction of prevailing winds. That is, supposing the hot-air and cold-air chambers to be so divided by the stop-dampers into as many distinct subchambers as 100 there are rooms in use at any given time, as to properly apportion the rarefiers among them, whereby downward drafts in the hot-air flues, and the robbing of the short ones 105 by the long are effectually prevented, the cold-air may, at pleasure either be withdrawn from the room at top or bottom, and returned to the same in a warm state, entering at top or bottom; or a supply may be 110 drawn from without and above the building where the atmosphere is purest, and discharged warm into the rooms, at top or bottom; the same being effected either with spontaneous ventilation through the upper 115 registers when the rooms are in use, or, without ventilation when the rooms are not in use, and it is desired to economize the heat. Or the vitiated air may be withdrawn from the rooms through either the 120 top or bottom register and discharged above the building, through the continuations of the hot-air flues without being allowed to re-enter the rooms; thus establishing a very efficient forced ventilation for either winter 125 or summer use.

The advantages gained, in the processes of both ventilation and warming by the above described arrangement of ventiducts in combination with the furnace and its ap- 130

pliances for properly tempering and moistening the ventilating currents are too obvious to need pointing out in a more especial manner.

5 On the twenty third of November, eighteen hundred and fifty eight, Letters Patent were granted to the undersigned for an improvement in the method of warming and ventilating buildings, with which the above 10 described apparatus may at first sight seem to interfere; but which upon examination of the claim, will be found to differ essentially from the present one in all that is here claimed as original. For, in the previous 15 patent, the claim granted, was for the peculiar arrangement and combination there specified, of the warm-air and cold-air ducts, registered openings and dampers in the hot-air flue; while in the present apparatus the 20 arrangement and combination of the ventiducts, registers and dampers are widely different, the cold-air duct being located as far as practicable in the room, from the warm-air duct instead of alongside of it, and continued 25 like the warm-air duct through to the top of the building, instead of terminating in the room, besides being provided with a couple of dampers; in which last respect, the arrangement of the former warm-air duct 30 also differs from that of the present; this, having two dampers, and that, but one.

I do not claim as new, the warming of the ventilating currents by passing them through pipes or chambers surrounded 35 wholly or in part by some heated medium, for this has frequently been done before in various ways; nor the mere drawing of the cold air from the rooms, either to be returned again in a warm state or discharged 40 from the building through some appropriate channel, for this has also been done before in a variety of ways; nor the arrangement and combination of the ventiducts, registers and dampers, so far as these are the same as

in my previous patent, alluded to above; nor 45 do I confine myself to the particular number form and size of the rarefying chambers, C—c—C', shown in the accompanying drawings. But

What I do claim as new and wish to secure 50 by Letters Patent is:—

1. The combination and arrangement of the fire-space with or without the grate, S, central flue, d, smoke damper, T, return flues, b, b, covering plates, V, V, V, openings 55 in plates, X, X, and exit opening, a, with or without the T pipe for returning the smoke to the chimney substantially as described, whereby the heat is economized and diffused over the surfaces of the rarefiers, C—c—C'. 60

2. The arrangement of the hot-air chambers, A, cold-air chambers, B, and connecting flues, A', B', in the walls of the furnace with or without the stop-dampers, M, N, O, O', substantially as described, whereby all or 65 any number of the rarefiers, C—c—C', may be connected at pleasure.

3. The combination and arrangement of the evaporating pans, P, P, flues, R, R, and registered openings, Q, Q, substantially as 70 set forth whereby any required degree of heat may be imparted to the water in the pans, and all of the warmed air made to pass directly over the surface of the same in its passage from the furnace. 75

4. The combination and arrangement of the rarefiers, C—c—C', hot-air-chambers, A, cold-air-chambers, B, connecting flues, A', B', stop-dampers, M, N, O, O', ventiducts, D—F, E—G, registers, H, I, J, K, and 80 dampers, L, above the registers, substantially as described, whereby the warming and ventilating currents may be perfectly controlled as set forth.
